UNITED STATES PATENT OFFICE.

HARRY COOK, OF MCKEESPORT, PENNSYLVANIA.

AUTOMATIC FEED-WATER REGULATOR.

SPECIFICATION forming part of Letters Patent No. 723,653, dated March 24, 1903.

Application filed November 3, 1902. Serial No. 129,830. (No model.)

To all whom it may concern:

Be it known that I, HARRY COOK, a citizen of the United States of America, residing at McKeesport, in the county of Allegheny and State of Pennsylvania, have invented certain new and useful Improvements in Automatic Feed-Water Regulators, of which the following is a specification, reference being had therein to the accompanying drawing.

This invention relates to certain new and useful improvements in automatic feed-water regulators, and has for its object the provision of novel means whereby when the water in the boiler lowers beyond the water-line which it is desired to maintain the valve or valves controlling the feed-line will be automatically opened so as to admit the water to the boiler and again raise the same to the desired water-line and also to automatically close the valve or valves when the desired water-line has been reached.

A further object of my invention is to provide means whereby the water will not be discharged into the boiler in its cold state, but will be heated to a considerable extent before being discharged into the boiler.

Still further objects of my invention are to provide a perfectly balanced valve, and other objects reside in the novel construction, combination, and arrangement of parts to be hereinafter more fully described, and specifically pointed out in the claims.

In describing the invention in detail reference is had to the accompanying drawing, forming a part of this specification, which drawing shows a vertical sectional view of my improved water-regulator applied in position on a boiler.

To put my invention into practice, I provide a valve body or casing 1, provided with an inlet 2, leading to the valve-chamber 3. The water-supply pipe 4 communicates with the inlet-port, being connected to the valve body or casing in any desirable or suitable manner, such as shown. The valve body or casing is provided with a pair of valve-seats 5, and communication is established from below the lower valve 6 to the chamber 8 above the upper valve 7 through a port or by-pass 9 in the valve body or casing. A union 10 is suitably connected to the lower end of the valve body or casing, and this union is also

securely fastened by the flange 11 and bolts passing therethrough to the boiler-casing 12, the union having an interiorly-threaded nipple 14, extending through the boiler-casing 12 and receiving the tubular extension 15, which is threaded therein and extends into the boiler. This tubular extension 15 is provided with an opening at one side and with a pair of lugs or ears 16, in which is pivoted the lever 17, the one end of which is pivotally connected to the valve-stem 18 and the outer end of which lever carries a float 19, the threaded stem 20 of which is threaded into the outer end of the lever and carries nuts 21-22 above and below the latter, whereby the float may be adjusted to the desired height. This float in practice is preferably made of a hollow copper ball, as this has been found to be the most desirable material.

The tubular extension 15 is provided with a flared or bell-shaped lower end 23, which is provided with slots or openings 24 to permit the water to escape from the tubular extension 15 into the funnel-shaped receptacle 25, which is carried on the screw-pin 26, secured to the lower end of the tubular extension 15, this screw-pin also carrying the corrugated pan 27, the pan and the funnel-shaped receptacle being secured on the pin by means of the nut 28.

The valve-stem 18 at its upper end carries a socket 29, provided with a stuffing-box 30, through which passes the regulating-stem 31. This regulating-stem 31 passes through a cover-plate 32 of the valve body or casing 1, through a suitable stuffing-box 33, carried by said top plate, and through a support 34 and is provided on its upper end with a suitable handle or operating-wheel 35. The regulating-stem at its lower end is provided with a head 36, which operates in the socket or cup 29, carried by the valve-stem 18.

In operation the water flowing through the inlet 2 will, providing the water-line in the boiler has lowered beyond the desired level, flow through the valve-body and through the tubular extension 24 into the receptacle 25. When this receptacle is filled with water, it is discharged onto the corrugated pan and flows into the boiler. Valves 6 and 7 will be open, due to the fact of the water-line being below the desired level and the float 19 being

consequently disengaged, so as to elevate the valve-stem 18 and open the valves 6 and 7. As the water reaches the desired level and the float 19 is carried upwardly thereby the 5 valves 6 and 7 will be engaged with their seats, and by reason of the water having been restricted during its flow into the boiler it will pass through by-pass or port 9 above the valve 7, and consequently maintain a perfectly balanced valve. If desired, the stem 31 may be screwed down so that the head 36 thereof will rest against the bottom of the socket or cup 29, so as to retain the valves in their closed position. The water being restricted in its passage, it becomes heated before being discharged into the boiler, and the drip-pan being corrugated the same flows off this pan slowly instead of being discharged rapidly therefrom.

20 Having fully described my invention, what I claim as new, and desire to secure by Letters Patent, is—

1. In an automatic feed-water regulator, the combination with a valve-body having a 25 pair of valve-seats and provided with a by-pass or port establishing communication with chambers above and below the valve-seats, said valve-body having an inlet-port, a valve-stem, and a pair of valves mounted on the 30 said stem, and a tubular extension connected to the valve-body and provided at its lower end with outlet-ports, and a float pivotally connected to the tubular extension and the valve-stem, substantially as described.
- 35 2. In an automatic feed-water regulator, a valve-casing provided with an inlet-port, a pair of valve-seats in said casing, and a port or by-pass in said casing, establishing communication above and below the valve-seats,
- 40 3. In an automatic feed-water regulator, a valve-stem extending through the valve-

body, a pair of valves carried by said stem to engage the seats, a socket or cup carried by the upper end of said valve-stem, a regulating-stem connected to said cup or socket, a tubular extension connected to the lower end 45 of the valve-body and extending into the boiler-shell, and an adjustable float pivotally connected to the tubular extension and valve-stem, substantially as described.

3. In an automatic feed-water regulator, 50 the combination of a valve-body provided with an inlet-port, a pair of valve-seats, a by-pass in the valve-body establishing communication above and below the valve-seats, a valve-stem, a pair of valves on said stem to engage 55 the valve-seats, an adjusting-stem connected to the valve-stem, a tubular extension connected to the lower end of the valve-body, an adjustable float pivotally connected to the tubular extension and to the valve-stem, a funnel-shaped receptacle carried by the lower end of the tubular extension, and a corrugated drip-pan carried by the extension below the funnel-shaped receptacle, substantially as described.

4. In an automatic feed-water regulator, the combination with the valve-body, formed with an inlet-port and a valve-seat, a tubular extension connected to the said valve-body, a valve-stem, a float operatively connected to 70 the said valve-stem, a receptacle carried by the lower end of the said tubular extension and a drip-pan arranged adjacent said receptacle.

In testimony whereof I affix my signature 75 in the presence of two witnesses.

HARRY COOK.
